UNITED STATES PATENT OFFICE

2,485,536

BOILER

Joseph D. Pierce, Chicago, and Charles E. Towner, Oak Lawn, Ill., assignors to Crane Co., Chicago, Ill., a corporation of Illinois

Application November 23, 1944, Serial No. 564,844

1 Claim. (Cl. 122—161)

1

This invention relates to a boiler. More particularly, it relates to the type embodying a small low capacity round boiler suitable for automatic firing with oil, gas or anthracite coal, and which possesses exceptionally high efficiency and low weight ratio due to its novel construction as hereinafter described.

It is an object generally to provide a heat generator for small homes in which a large part of the heating surface is directly exposed to the flame.

More particularly, it is an important object of this invention to provide a boiler in which its improved performance results from the combination of a relatively large amount of primary heating surface in the form of a fluted combustion chamber, entirely water jacketed, and a water backed heat trap formed by utilizing the dome of the boiler as a secondary heating surface with suitable integrally cast fins to direct the flow of the gases over the heating surfaces and ultimately through the baffled flue outlet to the chimney.

It is a further important object to provide a device in which there is relatively low stack temperature, high heat transmission and efficiency.

Another important object is to provide a very compact boiler having a low weight ratio in pounds of cast iron per square foot of output, particularly as compared to the conventional type of sectional boiler heretofore considered.

Another important object is to provide a boiler having a one-piece construction in which the machining required is reduced to a minimum and in which the manufacturing cost is relatively low.

A further important object is to provide a boiler in which a substantially tortuous form of baffle in the smokehood directs the flow of hot gases and products of combustion across the top of the boiler, thus using the latter portion as a secondary heating surface.

Another object is to provide a boiler sufficiently small and compact so as to permit its installation under work cabinets in utility rooms or even in kitchens.

Other objects and advantages of the construction will become more readily apparent in proceeding with the specification read in light of the accompanying drawings, in which

Fig. 1 is an exterior front elevation of a boiler embodying our invention.

Fig. 2 is a vertical section taken on the line 2—2 of Fig. 1.

Fig. 3 is a plan view of the boiler with the cover removed to show one form of baffle.

2

Fig. 4 is a sectional view taken on the line 4—4 of Fig. 2.

Fig. 5 is a fragmentary perspective view of the top of the boiler showing exteriorly the manner in which the cover and the flue outlet are applied.

Fig. 6 is a sectional view taken on the line 6—6 of Fig. 2.

Fig. 7 is a top view showing a modified form of heat trap.

Fig. 8 is a further modified form of heat baffle.

Referring now to Fig. 1, the cast boiler casing 1 is mounted upon the base 2 which may be either in the form of integral legs or else a cylindrical shell may be used for housing the refractory 3 shown in dotted lines and having a central aperture 4. Within the latter aperture the burner pot 5 or any suitable combustion equipment may be extended with the burner portion proper 6 projecting within the fire chamber 12 of the boiler. Obviously, depending upon whether oil burning, gas burning or anthracite burning devices are used with the boiler, the manner in which the type of burner just described is mounted will vary in size and shape. The term boiler or furnace is used interchangeable throughout this description.

At its lower portion adjacent to the support 2 the boiler is provided with an aperture 7 having suitable lugs 8 for mounting the conventional access door (not shown). At its lower portion the boiler is furnished with the respective connections 9 for the return and at the top 11 for the outlets to provide for the conventional circulation of the heated fluid within the boiler to a heating system (not shown).

As shown more clearly in Fig. 2, the interior of the fire chamber 12 is made with substantially vertical extended flutes 13, preferably but not necessarily tapering toward the upper portion and thereby varying in their relative capacities for the water at different levels, as shown by comparing Figs. 4 and 6. Certain of the flutes extend inwardly, as indicated at 14, and converge toward the center to form the aperture 15 (Fig. 2) at the upper dome portion of the boiler. Within the chamber 16 the novel heat trap is provided consisting substantially of the vertical extending walls or baffle arrangement 17, as shown more clearly in Fig. 3. The effect of such construction is to thereby provide for the elongated travel of the gases of combustion as indicated by the arrows then leading to the smoke outlet 18. Thus the heat trap is provided with water jacketed side walls and the top of the dome of the boiler or furnace is also water backed or jacketed, resulting

55

in higher efficiencies. The heat trap just described, of course, need not necessarily assume the detailed form described but may take the varied forms such as those modifications shown in Figs. 7 and 8. Therefore it is not the intention to be limited to the specific forms of baffles described in connection with Figs. 3, 7 or 8.

It will now become apparent that by the combination of the increased amount of area of surface within the combustion chamber 12 by employment of the fluted walls plus the novel means of trapping the heat at the upper portion of the boiler after it leaves the orifice 15 and reaches the heat trap 16, unusual high thermal efficiency is obtainable in a relatively small type of boiler. The boiler is easily assembled upon its supporting base, and at its upper portion, as shown more clearly in Fig. 5, a suitable smoke outlet 19 is attached to the side of the boiler for conducting combustion gases from the heat trap chamber 16 above which a cover 21 relatively snugly fitting is applied, resting preferably upon the top edges of the baffles.

Thus it will be apparent that there has been developed a low capacity boiler suitable for automatic firing in which the heating efficiency is relatively high, especially when considering its adaptability to small size boilers or furnaces. It should also be understood that many variations may be made in the construction and arrangement of the fluted walls in the combustion chamber and therefore it is the desire not to be limited other than as determined by the prior art when considering the appended claims.

We claim:

A substantially round boiler, having a smoke outlet and a combustion chamber, the said chamber having its outer limits defined by vertically fluted water jacketed walls converging at their upper portion to form the periphery of an aperture to provide for the escape of the hot products of combustion from the said chamber, the said boiler having a secondary heat transfer chamber communicating with the said aperture and having a floor comprising the top portion of the said water jacketed combustion chamber, the said heat transfer chamber having water jacketed side walls, the latter walls being extended integral portions of the walls of the said combustion chamber and being provided with a series of substantially vertical partitions integral with the said chamber floor and forming a tortuous path for the products of combustion and thereby providing a heat trap therefor.
